UNITED STATES PATENT OFFICE.

EDWARD TURGEON, OF THOMPSONVILLE, CONNECTICUT.

SAFETY APPLIANCE FOR ELEVATORS.

1,314,228.

Specification of Letters Patent. Patented Aug. 26, 1919.

Application filed November 20, 1918. Serial No. 263,408.

To all whom it may concern:

Be it known that I, EDWARD TURGEON, a citizen of the United States of America, and a resident of Thompsonville, in the 5 county of Hartford and State of Connecticut, have invented a new and useful Safety Appliance for Elevators, of which the following is a specification.

My invention relates to improvements in 10 safety appliance for elevators, and consists essentially of yielding, landing and elevator guards, landing trip mechanism and elevator trip mechanism with which said guards are respectively connected, oscillatory means operated by the elevator in ascending and descending, when and accordingly as said first-named or said second-named mechanism is released, to throw off or disconnect the power from said elevator, and setting and resetting 15 means, all of peculiar construction, together with such subsidiary and auxiliary parts and members as may be required or desired in order to render the appliance complete in 20 every respect, all as hereinafter set forth.

25 The primary object of my invention is to provide means automatically to cut off the power from an elevator, whether the latter be ascending or descending, whenever an animate or inanimate obstacle or obstruction 30 is thrust beyond the elevator floor into the elevator well when the elevator is ascending, on the one hand, or beyond the landing or floor into the path of the descending elevator, or is in the bottom of said well and 35 so in such path, on the other hand.

A further object is to provide such means which is applicable to practically any type of elevator, power, and power-controlling mechanism. My appliance is adaptable to 40 elevators of any size and regardless of the location and number of entrances thereto; to engine- and electric-motor-driven and hydraulic elevators; and to rope- or cable-controlled and electric-controlled elevators. 45 Still another object is to produce an appliance of this character which prevents the elevator from being started without setting the trip mechanisms, and from being restarted, when stopped by an obstruction, until such obstruction is removed, inasmuch as 50 the trip mechanism operated by said obstruction to stop the elevator can not otherwise be reset. An additional and valuable element of safety is thus introduced into the 55 appliance.

A further object is to afford protection to the obstruction from the appliance itself.

A still further object is to prevent damage to the appliance in the event the elevator continues to travel beyond a certain distance, in either direction, after the operation of the trip mechanism involved takes place. 60

Other objects and advantages will appear in the course of the following description.

A preferred embodiment of the invention, 65 whereby I attain the objects and secure the advantages of the same, is illustrated in the accompanying drawings, and I will proceed to describe said invention with reference to said drawings, although it is to be understood that the form, construction, arrangement, etc., of the parts and members in various aspects are not material and may be varied and modified without departure from the spirit of the invention. 70

In the drawings, in which like reference characters designate like parts throughout the several views, Figure 1 is a front elevation of an elevator well and elevator, showing a practical embodiment of my safety 80 appliance as aforesaid, the same being within said well and applied to said elevator, and a landing or floor appearing in section; Fig. 2, an operation detail of the neutralizer cable for the starting and stopping cable of 85 the elevator, with associated parts and members; Fig. 3, another operation detail of said neutralizer cable with said associated parts and members; Fig. 4, an inside elevation of a portion of the left-hand side or wall of 90 the well, and of the members on that side, a fragment of said floor appearing in section; Fig. 5, a similar view looking toward the right-hand wall of said well; Fig. 6, an operation detail of the rockers and their 95 connections, shown in the preceding view, intermediate portions of the wall and of such connections being broken out; Fig. 7, a bottom plan of the neutralizer and other members at the top of the well; Fig. 8, a 100 bottom plan of the elevator and attached parts; Fig. 9, an elevation of the right-hand side of said elevator and attached parts; Fig. 10, a fragmentary section through the elevator floor or platform, taken on lines 105 10—10, looking in the direction of the associated arrow, in Fig. 1; Fig. 11, another fragmentary section through said platform, on lines 11—11, looking in the direction of the associated arrow, in Fig. 10; Fig. 12, 110

an enlarged, central, vertical section through a portion of the landing trip mechanism, on lines 12—12, looking in the direction of the associated arrow, in Fig. 5, a fragment of 5 the associated rack also being shown; Fig. 13, an enlarged, side elevation of said mechanism, as viewed from the left, portions of the rock-shaft being broken out; Fig. 14, an enlarged, side elevation of the setting 10 device of said mechanism, as viewed from the right; Fig. 15, a front end or edge elevation of said device, taken through the rock-shaft on lines 15—15, looking in the direction of the associated arrow, in Fig. 15; Fig. 16, an enlarged, front elevation of 15 the trip or latch elements of the aforesaid mechanism, the front plate or cover being removed; Fig. 17, an operation view of the parts shown in Fig. 12; Fig. 18, a corresponding operation view of the parts shown 20 in Fig. 13; Fig. 19, another operation view of said parts shown in Fig. 12; Fig. 20, an operation view of the parts shown in Fig. 16; Fig. 21, an enlarged, fragmentary section 25 through said elevator platform, taking in the front corner which is opposite to that involved in Figs. 10 and 11, and taken on lines 12—12, looking in the direction of the associated arrow, in Fig. 22; Fig. 22, an enlarged, side elevation of said platform, 30 and of the elevator trip mechanism attached thereto and carried thereby, as viewed from the right; Fig. 23, an enlarged, top plan of said last-named mechanism, obscuring 35 parts of the platform and bracket above being broken away; Fig. 24, an operation view of the parts shown in Fig. 21; Fig. 25, a corresponding operation view of the parts shown in Fig. 22, and, Fig. 26, a side elevation 40 of an electric switch and means to open the same through the medium of my appliance.

In illustrating the application of my invention, I have deemed it necessary to show 45 merely right- and left-hand, side walls 1 and 2, respectively, a rear wall 46, and a top 3, of an elevator well, without any of the customary inclosing members, including gates or doors, at the front, a single landing or floor 4 in front of such well, and a 50 very simple form of elevator. It is to be understood, however, that, in practice, exposed and unprotected spaces at the sides of the well in front will be closed, there may 55 be any number of floors or landings, and the elevator may be as elaborate in structure and furnishings as desired. I have, furthermore, shown the elevator raised to an unusual height in the first view, but this is 60 done in order to expose more of the appliance in said view, and a clear understanding of the operation is not thereby interfered with.

It is assumed, in this case, that the source 65 of the motive power for the elevator and

the means of control for said power are above the top 3.

Although the entrance to and exit from the elevator, in the present example, are presumed to be at the front and there only, 70 the appliance is equally well adapted for and adaptable to an elevator which opens on any other one side, or on any two or even more sides, it only being necessary to arrange, locate, or extend the yielding 75 guards accordingly.

The walls 1 and 2 are provided inside with vertical elevator guides 5—5.

The elevator, which is designed to travel up and down between the guides 5, consists 80 of a floor or platform 6, and two uprights 7 at the sides, which uprights are connected by a cross bar 8. Braces appear at 9—9. The uprights 7 extend above and below the platform 6, and are provided with four, 85 short channel-irons 11^a, two on each upright, to engage the guides 5 and hold the elevator in place as it moves up and down.

In the center of the top of the cross bar 90 or beam 8 is an eye-bolt 13, and a power chain or cable 14 is attached at one end to the same. The cable 14 passes over a sheave 16, under a sheave 17, and up through the top 4 to the winding mechanism which is not shown. The sheaves 16 and 17 are 95 mounted on two spindles 18 which are journaled in two pairs of brackets 19, the latter being secured to the underside of the top 4.

Two vertical reaches, front and back, of a 100 power-controlling rope or cable, are represented at 20 and 22, respectively. This cable is in front of the left-hand guide 5, and passes under a sheave 23 which is located near the bottom of the elevator well. The sheave 23 is mounted on a stud 24 that projects inwardly from a bracket 25 which is secured to the inner face of the wall 2. The reaches 20 and 22 of the aforesaid cable extend upwardly from the sheave 23, past the 110 elevator and within convenient reach of an operator on the platform 6, to the top 3, and through said top to the power-controlling device, apparatus, or mechanism, which does not appear in connection herewith. For the 115 purposes of this description, it is to be understood that, when the reach 22 is pulled down or the reach 20 pulled up, from neutral position, the elevator is caused to ascend, and, when said reach 20 is pulled down or said reach 22 pulled up, from such 120 position, said elevator is caused to descend, while the returning of the reaches to neutral position causes the elevator to stop in either case.

An equalizer or neutralizer, for the 125 reaches 20 and 22, comprises a cord or cable 26, which has one end attached to a pin 27, Fig. 5, set in the wall 1 inside of the well and near the top 3, and at the other end has 130 a branch 28 that extends and is attached to

- said reach 20 and a branch 29 that extends and is attached to said reach 22. A rocker 30, presently to be described, is pivoted at 31 to the wall 1 just below the top 3, and carries a vertical sheave 32. A bracket 33 is secured to the top 3, underneath the latter, and has a stud 34 upon which a horizontal sheave 35 is mounted, such sheave being back of and a little higher than the sheave 32.
- 10 A bracket arm 36 is pivotally supported at 37 from the top 3—see Fig. 7. At the right-hand end of said arm is a stud 38 upon which a horizontal sheave 39 is mounted. Means is provided to impart a movement or 15 a tendency to a movement to the arm 36 that will carry rearwardly the end of the arm 36 which supports the sheave 39, and yielding to retain said arm in contact with a stop 40, which depends from the top 3 in 20 front of a portion of the arm which is at the left of the pivot 37, such as a spring 41 having its rear end attached to the left-hand end of said arm and its forward end to a pin 42 projecting inwardly from the wall 2. For 25 the sake of clearness the tension arm 36 and the spring 41 are omitted from Fig. 1. A bracket 43 is secured to the inside face of the wall 2 about on a level with the sheave 32 across the well, and such bracket has a stud 30 44 upon which a vertical sheave 45 is mounted.
- The neutralizer cable 26 passes forward from the pin 27 to the sheave 32, up in front of said sheave and rearwardly to the sheave 35, partially around the latter and obliquely to the sheave 39, which latter is located by the arm 36 approximately midway between the walls 1 and 2 and near the back side (46) of the well, obliquely to the sheave 45, and 40 over the top of said last-named sheave. With this end of the cable 26 the upper ends of the cable branches 28 and 29 are connected, while the lower ends of said branches are connected with or attached to 45 the cable reaches 20 and 22, in the manner previously explained. In Fig. 4 the neutral positions, as when the elevator is stationary or the shift is made to stop it, of the cable reaches 20 and 22 and the branches 28 and 50 29 are represented; in Fig. 2 the positions which such members assume, when the shift is made to cause said elevator to ascend and while it is ascending, are represented; and in Fig. 3 the positions of said members, when 55 the shift is made to cause said elevator to descend and while it is descending, are represented. There is sufficient slack in the cable 26, when the reaches 20 and 22 and the branches 28 and 29 are in neutral position, 60 and the rocker 30 with its sheave 32 is in initial position, with the axis of said sheave in approximately the same vertical plane with the axis of the pivot 31, as shown in Figs. 4 and 5, to enable the shifts, which are 65 represented in Figs. 2 and 3, to be made. Each of such shifts takes the aforesaid slack out of the cable 26. It follows, therefore, that, if the rocker 30 be actuated on its pivot 31 to carry the sheave 32 forward, said sheave, in its forward movement, lengthens 70 the reach of the cable 26 which is between the pin 27 and said sheave, by shortening that portion of said cable which extends from said sheave around the sheaves 35 and 39 and over the sheave 45 to the branches 28 75 and 29, and, in shortening said second-named portion of said cable, draws up whichever of said branches is attached to the reach 20 or 22 that is in downward shift, and with it such reach, until both of said 80 branches are positioned with their lower ends even with each other. Thus the reaches 20 and 22 are shifted to neutral position and the elevator is stopped.
- The tension arm 36 does not affect the 85 cable 26 under ordinary conditions or circumstances, since the spring 41 is sufficiently strong to enable the neutralizer to perform its various functions without swinging said arm out of contact with the stop 40, but in 90 case said cable is suddenly acted on by the rocker 30, or in the event said cable should be drawn forward too far by said rocker, said spring yields for the protection of the reaches 20 and 22 and the equalizer itself. 95 In this last event the cable 26, through the medium of the sheave 39, swings the arm 36 away from the stop 40, thus shortening the distance between the sheaves 35 and 45 by way of said first-named sheave.
- 100 As soon as the rocker 30 is returned to initial position, or is permitted to be so returned, the cable 26 is relaxed once more, so that the hand-operated or hand-controlled, power-controlling elements are left ready 105 for use in the usual and customary manner.
- The rocker 30 forms part of an oscillatory actuator for the cable 26, or for an electric switch hereinafter described. There is a second rocker 47, which is pivotally attached 110 at 48 to the wall 1, or to a face-plate 49, interposed between the inner face of said wall and said rocker, which is also the case with the rocker 30, such plates appearing in Fig. 1. The rockers 30 and 47 are horizontally or approximately so, and pivotally mounted intermediate of their ends. The other elements of the said actuator, besides the two rockers, consist of a chain or cable 50, which connects the front ends of said 115 rockers, chains or cables 51 and 52 which respectively depend and rise from the rear ends of said rockers, and a rod 53 to the top and bottom ends of which the bottom terminal of said cable 51 and the upper terminal of said cable 52 are respectively attached. The pivot 48 is in the same vertical plane with the pivot 31, and the cables 51 and 52 connected by the rod 53, with said rod, are parallel with the cable 50. The ac- 120
- 125 130

4

tuator cables are here connected with the rockers by means of pins 54. The pins 54 project to the left from the rockers at or adjacent to the ends thereof. It is now 5 clear that force applied to this actuator at any point, as to the rod 53, or to the cable 50, in a manner to move said rod or cable in the direction of its length, is transmitted to the actuator as a whole and causes it to 10 rock on the pivots 31 and 48. Such rocking movement does not throw the front and rear rocker connecting members out of parallel relationship, and the amount of said movement required for my purpose is so slight, 15 comparatively, that the decrease in distance between said connecting members, produced by said movement, is negligible. The actuator is disposed in Fig. 6 in its extreme operative position. When the actuator is caused 20 to assume this position, the neutralizer is caused to shift the cable reaches 20 and 22 to neutral position, and by so doing to stop the elevator, in the construction which includes said equalizer.

25 Extending below the edge of the floor 4, which is directly in front of the elevator well, is a horizontal, yielding or flexible member, in the form of a chain, cable, cord, or the like, the same being represented at 55. 30 This is the primary element of the landing guard. And extending below the front edge of the elevator platform 6 is a similar member, in similar form, which is represented at 56. This second flexible member is the primary element of the elevator guard. A secondary element of the landing guard consists of a plurality of vertical chains, cords, or the like, the same being represented at 57, which have their lower ends fastened to the cord 55, and their upper ends fastened to the lower edge of a thin plate 58, which latter is secured to the edge of the floor 4 above said cord. And a secondary element 40 of the elevator guard consists of a plurality of vertical chains, cords, or the like, the same being represented at 59, which have their lower ends fastened to the cord 56, and their upper ends fastened to the bottom edge of a thin plate 60, which latter is secured to the front edge of the platform 6. A tertiary element of this elevator guard consists of a netting of chains, cords, or the like, or an equivalent member or members, the same being here represented, at 61, in the form of a netting of cords—see Figs. 8 and 9. In these views the cord netting 61 is attached at the front end to the cord 56, and at the back end to a row of pins 62 underneath the 50 platform 6 adjacent to the back edge thereof.

60 Trip mechanisms, presently to be described, are interposed between the cords 55 and 56 and the actuator which causes the power to be shut off from the elevator. 65 Each of these mechanisms is tripped by a slight pull on the cord 55 or 56 which is connected therewith, as will subsequently be explained, and such a pull may be imparted to the cord either by a direct contact therewith, or through the medium of any of the 70 cords 57, or of any of the cords 59 or of the netting 61, as the case may be. Any object which extends beyond the front edge of the platform 6, when the latter is ascending to the floor 4, either encounters the cord 75 55 or the cords 57 and so tends to draw said cord 55 inwardly at the ends, and any object which extends into the well from the adjacent edge of said floor, when said platform is descending to said floor, is either 80 contacted with by the cord 56 or encounters the cords 59 and so tends to cause said cord 56 to be drawn inwardly at the ends. Likewise, an obstruction below the platform 6, in the bottom of the well, is contacted with 85 by the netting 61, when the elevator is descending, and acts on the cord 56 to draw it inwardly at the ends. It will presently appear why the cords 55 and 56 are drawn inwardly at the ends whenever they are subjected to strain at intermediate points. Owing to the construction of the guards, of 90 which the cords 55 and 56 are the primary elements, which construction has just been described, the aforesaid strain is effective, 95 whether applied from below or from above, or from behind as when the netting 61 is the medium. And this would be true if the strain were applied from any other direction.

100 Before describing the trip mechanisms I desire to point out several additional structural parts and members.

Fastened to the inside of the wall 1 at the front edge is a vertical bracket 63 which is 105 provided on the front with a cover 64. The bracket 63 projects forward under the floor 4, and is located a short distance below said floor. A vertical bracket 65 is fastened to the wall 2, on the inside at the front edge, 110 and just below the level of the underside of the floor 4—see Figs. 1 and 4. A spindle 66 is journaled in the bracket 65, and a sheave 67 is mounted on said spindle. The arrangement is such that the sheave 67 is at 115 right-angles to the wall 2, and the bottom of said sheave is in line with the horizontal portion of the cord 55. An angular, corner bracket 68 depends from the right-hand, front corner of the platform 6, and a similar 120 bracket 69 depends from the left-hand, front corner of said platform. As shown in Figs. 8, 10, and 11, a sheave 70 is mounted on a stud 71 which projects inwardly from the front of the bracket 69, such sheave being 125 parallel with such front, and the bottom of said sheave being in line with the main horizontal portion of the cord 56. And a sheave 72 is mounted on a stud 73 which projects inwardly from the side of the bracket 69, 130

said sheave being at right-angles to the sheave 70 and at a higher elevation. An angular, horizontal bracket 74 is secured to the underside of the platform 6, at the right-hand edge a short distance behind the bracket 68. The bracket 74 is provided at the front end of its side, on the outside, with a vertical abutment 75, from the upper and lower ends of which arms 76—76 extend rearwardly.

It may be observed here that the positions of the abutment 75 and the arms 76 are such that the actuator cable 50 passes through said arms, which are perforated, as represented at 77—77 in Figs. 22, 23, and 25, for that purpose, and directly back of said abutment. Under normal conditions the members 75 and 76 travel up and down with the elevator without interfering with the cable 50, and the latter is free to move up and down in the openings 77.

A bearing bracket 78 is fastened against the inside face of the wall 1 back of the bracket 63. Mention may also be made, before taking up the landing and elevator trip mechanisms, which will be done in the order named, of a sheave 79 and a rack 80. The sheave 79 is mounted on a stud 81 which extends inwardly from the wall 2, as clearly shown in Fig. 4. The sheave 79 is positioned at a higher elevation than the adjacent sheave 67, and at right-angles thereto. The rack 80 is secured to the front side of the right-hand elevator upright 7, and arranged with the teeth at the right and projecting in that direction beyond said upright. The fragments of this rack which appear in Figs. 12, 17, and 19, are rear elevations of the same, detached, but their position relative to the landing trip mechanism in each view is correct, and they are necessary in order to obtain a clear, complete, and comprehensive understanding of said mechanism. The rack 80 is very closely identified with the landing trip mechanism, and may be said to form a part thereof.

Referring more particularly to Figs. 12 to 20, inclusive, it will be seen that the landing trip mechanism comprises, besides the rack 80, a horizontal rock-shaft 82 journaled in the brackets 63 and 78 and having an upwardly-directed crank-arm 83 at the rear end, a spring-pressed operating arm 84 and latch 85 at the front end of said rock-shaft, a short, horizontal rod or swivel 86 carried at the upper end of said crank-arm, a slide 87 rigidly attached to the actuator rod 53, a vertical, fixed guide 88 for said slide, an arm 89 pivotally connected at the top with said slide and having an inwardly-extending tooth 90 at the bottom to engage the teeth of said rack, a rod 91 rigidly attached at the top to a forwardly-extending lug 92 at the base of said arm, and operatively connected with said swivel, and a fixed cam 93.

In addition to these parts and members, there is a setting device comprising a block 94 loosely mounted on the rock-shaft 82, an upstanding lever 95 pivoted at 96 to said block, and a lug or pin 97 projecting from said rock-shaft into the path of a lug 98 at or adjacent to the base of said lever.

The arm 84 is rigidly attached to the front end of the rock-shaft, in front of the bracket 63, and the greater length of said arm is at the left of said rock-shaft. The latch 85 has its base pivotally connected at 99 with the arm 84 at the left-hand end, and extends upwardly from said arm. A spring 100 is attached at the bottom to the arm 84 at a point beyond the rock-shaft 82 to the right, and at the top to the latch well up toward a hook 101 which is formed in the right-hand edge of said latch near the top. A lug 102 projects from the front of the bracket 63, adjacent to the right-hand edge thereof, and is in the path of the hook 101 when the latch 85 is actuated upwardly, by the rock-shaft 82 and the arm 84, and rocked on its pivot 99 toward said lug, by the spring 100. The spring 100 has a constant tendency to cause the rock-shaft 82 to be rocked to the left, but is prevented from so doing while the hook 101 is in engagement with the lug 102. As soon, however, as the latch 85 is drawn away from the lug 102 and the hook 101 clears said lug, the spring 100 draws the arm 84 upwardly at the short end, and so rocks the rock-shaft 82 to the left—see Fig. 20. Normally the latch 85 is in engagement with the lug 102, and the connected parts are disposed accordingly, as shown in Fig. 16.

The right-hand end of the cord 55 is attached to the latch 85 at an intermediate point, and said cord passes directly across to and under the sheave 67, up and over the sheave 79, and down to a weight 103 which is suspended from said cord at this end. The weight 103 is heavy enough to permit the cord 55, when strained, to spring the latch 85, while at the same time affording yielding means whereby continued pressure on said cord, in the event the elevator continues to travel some distance after the power is shut off, simply causes the cord to draw up the weight without injury to the thing that is in contact with the cord. The cord 55 could be forced clear to the bottom edge of the plate 58, by the ascending elevator and an interposed object, without seriously injuring such object, but before any such extreme displacement can occur the elevator comes to a stop.

A collar 111 is secured to the cord 55 at a point which enables it to bear against the right-hand edges of the front of the bracket 65 and a bridge-piece 112, which latter is attached to said bracket front, and so to relieve from the weight 103 that portion of

said cord that is at the right of said collar. The length of cord 55 to the right of the collar 111 is sufficient for the proper action of the latch 85.

5 The cover 64 is cut out at 113 to receive a portion of and accommodate the spring 100, and the movement of said latch, when tripped, is limited by said spring and the contiguous edge of such opening, even when 10 said cord is under stress from the weight 103.

A collar 104 and a set-screw 105 are applied to the swivel 86 in front of the crank-arm 83. The swivel 86 is free to rotate in the crank-arm 83, and is pierced transversely, behind said crank-arm 83, to receive the rod 91, which latter works up and down through said swivel. The guide 88 is a rib at the rear edge of a bracket 106 which is fastened to the inner face of the wall 1, 15 in front of the right-hand elevator guide 7. Horizontal arms 107—107, at the top and bottom of the bracket 106, serve as guides for the rod 53, such arms being perforated to accommodate said rod. The slide 87 has a 20 vertical slot 108, in the side thereof which is adjacent to the vertical portion of the bracket 106, to receive the guide 88, and said slide operates between the arms 107. The slide 87 is secured to the rod 53 by means of 25 a horizontal pin 109, and the same pin serves as the pivot for the arm 89, there being a vertical slot 110 in said slide to receive the upper terminal of said arm. The arm 89 extends downwardly from the slide 87, 30 in front of the rod 53, and the tooth 90, at the base of said arm, projects rearwardly into position to be thrust into engagement with the teeth of the rack 80. When the slide 87 is at the lower end of its travel, the 35 rockers 30 and 47 are positioned horizontally or approximately so, and, when said slide is at the upper end of its travel, said rockers are tilted forward, as shown in Fig. 6. The arms 107, therefore, limit the move- 40 ment of the actuator.

The cam plate or stationary cam 93 depends from an inwardly-extending arm 114 at the top of a plate 115 which is secured to the wall 1 below the bracket 106. The rod 53 extends through and operates in the arm 114, the bottom being perforated, like the arms 107, for the accommodation of said rod. The cam 93 projects into the path of the tooth 90.

55 The block 94 is held against endwise movement, on the rock-shaft 82, by means of the pin 97 which is at the front end of said block, and a pin 116 which projects from said rock-shaft at the rear end of said block. 60 The lever 95 is pivoted to the block 94 between the latter and the wall 1, and the lug 98 projects forwardly over the pin 97. The latter has an upward inclination at all times. Normally the lever 95 stands approximately 65 upright. A supporting guide 117 is pro-

vided for the lever 95, such guide being fastened against the inside face of the wall 1.

The mechanism illustrated in Figs. 12 and 13, also the setting device shown in Figs. 14 and 15, are in normal or initial position.

The trip mechanism just described operates in the following manner: When the latch 85 is tripped by the cord 55, the spring 100 causes the rock-shaft 82 with its crank-arm 83 to rock to the left, and the arm 89 is 70 swung on its pivot 109 by said crank-arm in the same direction, through the medium of the swivel 86 and the rod 91, until the tooth 90 engages the rack 80, as shown in Figs. 17 and 18. Assuming that the elevator be rising at this time, the rack 80, acting through the tooth 90, the arm 89, the slide 87, and by this means and in this manner the actuator is rocked or tilted to shut off the power 80 from the elevator. The elevator can not be started again until the actuator is rocked back to normal position, and this can not be done until the aforesaid trip mechanism is reset, because of the elevated position of the 85 slide 87 and the existing engagement between the tooth 90 and the rack 80.

When the rock-shaft 82 is rocked to the left, the pin 97 throws the lever 95 rearwardly. To set or reset the landing trip 95 mechanism, simply grasp the lever 95 and force it forward on its pivot 96. This action causes the pin 97 to be forced downwardly by the lug 98. The pin 97 carries with it the rock-shaft 82, rocking the same to the 100 right. The partial rotation to the right of the rock-shaft 82 causes the tooth 90 to be withdrawn from engagement with the rack 80, and causes the latch 85 to be reengaged with the lug 102. The slide 87 and the rod 105 53 are free to descend now, when the actuator is restored to initial or normal position, and the mechanism is ready to be tripped again by the cord 55.

In the event the upward travel of the 110 elevator be considerable, after the power is shut off by the action of the landing trip mechanism, the tooth 90 is carried into engagement with the cam 93, and by said cam forced out of engagement with the rack 80, 115 as shown in Fig. 19. This occurs before the block 87 reaches the upper arm 107, and prevents breaking or straining any of the parts. When the tooth 90 is forced to the 120 right by the cam 93, it brings about the automatic resetting of the trip mechanism, of which said tooth forms a part, inasmuch as the arm 89 is swung in the same direction, and carries with it the rod 91, swivel 86, crank-arm 83, and rock-shaft 82, and the latter causes the latch 85 to be reengaged 125 with the lug 102. The rod 53 can now descend, as when the resetting is done with the lever 95. Unless the obstacle which causes the tripping of the trip mechanism be re- 130

moved, said mechanism can remain set only so long as the tooth 90 is in engagement with the cam 93, as will be readily seen, so that the resetting, in order to be effective, must 5 as a rule be done by hand and after removing the tripping obstacle.

It is to be remembered, in considering the explanation of the operation of this trip mechanism, that the parts appearing in 10 Figs. 12, 17, and 19 are viewed from behind.

Referring next to Figs. 21 to 25, inclusive, more especially, for the elevator trip mechanism, it will be observed that such mechanism comprises an upwardly spring-pressed, 15 vertical plunger 118, a spring-pressed latch 119 for said plunger, an oscillatory wedge-block 120 which co-operates with the abutment 75, the latter really constituting a part of this trip mechanism, and an arm 121. 20 The abutment 75 and the wedge-block 120 form a clutch for the actuator cable 50.

The plunger 118 is arranged to slide in two perforated lugs or arms 122 which extend from the side of the bracket 68 parallel 25 with the front of said bracket. A horizontal pin 123 extends through the plunger 118 below the arm 122, and projects into and operates in a vertical slot 124 in the front of the bracket 68. The pin 123, by reason of 30 its extension into the slot 124, assists in preventing the plunger 118 from turning on its axis. A spring 125 encircles the plunger 118 between the lower arm 122 and the pin 123. The upper terminal of the plunger 118 35 has a slot 126 therein, which extends through from front to back, and a pin 127 is inserted in said plunger and arranged across said slot at the upper end.

The latch 119 is pivoted at the lower end, 40 at 128, to the back side of the front of the bracket 68, and said latch has a hook 129 at the upper terminal to engage the pin 124. The latch 119 may have a lug 130 at the base provided with a rearwardly-extending pin 45 131, which pin is adapted to be engaged by the spring 125, for the purpose of yieldingly retaining said latch or its hook 129 in contact with the pin 123, but I prefer to rely mainly for such contact upon a spring 132. 50 The spring 132 is attached to two pins 133 set in the front of the bracket 68 and projecting back of such front, and said spring is arranged to bear on the latch 119 in such a way as to urge the hook 129 into contact 55 with the pin 123. The latch 119 is urged by the springs 125 and 132 toward the right, it being remembered that the parts which appear in Figs. 21 and 24 are viewed from behind.

60 In Fig. 22, a lip 134 on the side of the bracket 68, between the arms 122, is broken off to disclose the latch 119, the right-hand edge of which is shown, and the front of said bracket is cut away to show the slot 65 124.

When the plunger 118 is forced downwardly, against the resiliency of the spring 125, the latch hook 129 passes over the contiguous terminal of the pin 123 and holds said plunger in depressed position. And 70 when the latch 119 is rocked to the right, against the resiliency of the springs 125 and 132, the hook 129 slips off of the pin 123 and releases the plunger 118 to said spring 125, which immediately forces said plunger 75 upwardly. The normal positions of the parts are shown in Figs. 21 and 22.

The cord 56 has its right-hand end attached to the latch 119, and a pull on said cord trips said latch and releases the plunger 80 118, as shown in Figs. 24 and 25. The cord 56 extends straightaway from the latch 119 across to and part way around the sheave 70, up to and over the sheave 72, and rearwardly to a tension member, which here is 85 a spring 135—see Figs. 8, 10, and 11. The rear end of the spring 135 is fastened at 136, Fig. 8, to the underside of the platform 6, and the other end of said spring is attached to the cord 56. The spring 135 performs a 90 similar function for the cord 56 that the weight 103 performs for the cord 55; and said cord 56 is provided with a collar 137, which is similar to and for a similar purpose as the collar 111. The collar 137 bears 95 against the right-hand edges of the bracket 69 and a bridge-piece 138 which is secured to the back side of the front of said bracket.

The wedge-block 120 is pivotally attached near the rear end, at 139, to the depending 100 side of the bracket 74. There is a longitudinal slot 140 in the wedge-block 120, through which at the rear end the pivot 139 passes into the aforesaid side of the bracket 74, and a spring 141 is located in said slot 105 between said pivot, which such spring bears against, and the front end of said slot. A lug 142 projects from the bracket side into a notch 143 in the upper edge of the wedge block 120, adjacent to the rear end thereof, 110 and the back wall of such notch forms a lug 144 which contacts with and bears against said first-named lug. The notch 143 is larger than the lug 142, being sufficiently large to permit all necessary play on the part of 115 the wedge-block 120. The front end or nose of the wedge-block is in quite close proximity to the abutment 75, and the actuator cable 50 is received between such nose and abutment. A setting lever 145 rises from 120 the wedge-block into position to be grasped by the operator on the elevator platform, and it may be observed here, also, that the setting lever 95 is in position usually to be grasped by said operator, when the elevator 125 is stopped by reason of the displacement or the diverting of the cord 55. In some rare cases the elevator might be stopped in a position where the operator on the platform 6 could not reach the lever 95, and in such 130

cases this lever would have to be reached from some other point.

The rear terminal of the arm 121 is secured to the inside face of the wedge-block 120, as represented at 146, in Figs. 22, 23, and 25. The arm 121, after leaving the wedge-block, extends forward and has its front end introduced into the plunger slot 126. The side of the bracket 74 is cut out 10 at 147 to accommodate the rear end portion of the arm 121, and the latter is offset at 148, Fig. 23, to enable it to clear the front end portion of said bracket side.

When the plunger 118 is released from 15 the latch 119, and rises under the impulse of the spring 125, the front end of the arm 121 is carried up with said plunger, and said arm in turn rocks the wedge-block 120 on the pivot 139, and causes it to grip with its 20 nose the cable 50 between such nose and the abutment 75, said cable being forced by said nose tightly against said abutment—see 25 Figs. 24 and 25. The cable 50 is thus carried down with the descending elevator, and the actuator operated to shut off the power.

While the cable 50 is in the grasp of the wedge-block 120 and the abutment 75, the actuator can not be thrown or drawn back 30 to normal position, consequently the elevator can not be started until this trip mechanism is reset. The said mechanism is set or reset simply by forcing the lever 145 forward. This action rocks the wedge-block 120, on 35 the pivot 139 and the lug 144 on the lug 142, downwardly, releases the cables 50, and, through the medium of the arm 121, forces the plunger 118 down until the latch hook 129 slips over the pin 123. The mechanism 40 is now normally disposed, as illustrated in Figs. 21 and 22. The mechanism is now ready for a repetition of the tripping action and stopping operation.

The movement of the latch 119, when 45 tripped by the cord 56, is limited by the upper arm 122, with which the top of said latch or of the hook 129 then comes into contact, but not until said hook has released the pin 123.

50 The upward movement of the wedge-block 120, with the attached and associated parts, is limited and may be varied by a screw 149 tapped into and through the upper arm 76. The wedge-block strikes the bottom of the 55 screw 149 when said wedge-block is forced upward. By turning the screw 149 up or down the movement of the wedge-block is increased or decreased accordingly.

In the event the elevator continues to descend, after the power is shut off, to an extent that would ordinarily threaten injury to the actuator, the cord 50 of which is in the grasp of the wedge-block 120 and abutment 75, the spring 141 becomes an important factor, since it affords the needed relief

and said wedge-block and abutment slide down on said cable without breaking, unduly straining, or otherwise injuring either the cable or other parts of the actuator. The spring 141 normally forces the wedge-block 70 forward as far as the pivot 139 and the rear end of the slot 140 permit, and so holds said wedge-block, exerting sufficient pressure to enable the shifting operation to be performed, but not pressure enough to prevent 75 slipping on the cable 50 after such shifting operation.

In the event the elevator is started and stopped by an electric controller, an electric switch such as is shown in Fig. 26 is used to 80 open and close the electric circuit. This view is a side elevation. The switch herein shown consists of a fixed contact member 150, an oscillatory contact member 151 pivotally attached at 152 to an arm 153, of insulating material, which projects from said first-named member, and a spring 154 arranged to force said member into contact with said member 150, and so to close the circuit. Wires 155 and 156 are attached, respectively to the contact members 150 and 151. An actuator rocker 157, generally similar to the rocker 30, is shown. This rocker has pivoted thereto at 163 an arm 158. The arm 158 extends forwardly toward the contact member 151, on a plane which is below the pivot 152, and a plunger 159, of insulating material, extends from said arm into contact with said member. The arm 158, forward of the pivotally-attached, rear terminal, is tubular, and the rear terminal portion of the plunger 159 fits and slides within the tubular part of said arm. A spring 160 is introduced into the arm 158, between the end of the passage 90 therein and the inner end of the plunger 159, to afford a yielding contact between said plunger and the member 151, and absorb any undue shock that may be experienced by the parts when they are operated. 100 A support 161 having a swivel, supporting guide 162 for the plunger 159 is provided to maintain the arm 158 and said plunger in the position mentioned above. A vertical series of holes 164 is provided, in the rocker 115 157, to permit the pivot 163 to be adjusted for the purpose of varying the stroke of the arm 158 and plunger 159, when said rocker is tilted forward. Cables 50 and 51, for 120 which there are two pins 54, are employed in this as in the other case. Obviously the spring 160 when expanded should be somewhat stronger than the spring 154.

When the rocker 157 is tilted forward, by either trip mechanism, it advances the arm 125 158 and plunger 159, contracting and so increasing the power of the spring 160, forces the tail of the contact member 151, against the resiliency of the spring 154, toward the adjacent part of the contact member 150, 130

and separates said first-named contact member from said second-named contact member, thus breaking the circuit and shutting off the power from the elevator. Upon the 5 release of the actuator, of which the rocker 157 is a part, from the trip mechanism that caused the same to operate, the springs 154 and 160 act to force back the plunger 159 and arm 158 and to restore said rocker with 10 said actuator to initial position, and said spring 154 at the same time rocks the member 151 into contact with the member 150, and closes the circuit through the switch.

The general operation of this appliance as 15 a whole will be quite well understood from the foregoing description and explanation, hence the same need be but briefly outlined further.

Assuming that the cable reaches 20 and 22 20 and the cable branches 28 and 29 are disposed as in Fig. 2, when the elevator is ascending, and that the platform 6 is approaching the floor 4, and assuming, furthermore, that the cord 55 is deflected, either 25 by force applied to some one or more of the cords 57 or directly to said cord 55 itself, the latter exerts a pull on the latch 85 and trips the same, when the spring 100 causes the rock-shaft 82 to be partially rotated, 30 and in turn to cause the tooth 90 to be thrown into engagement with the ascending rack 80. The rack 80 carries up the tooth 90, arm 89, and slide 87, and with the latter the rod 53. The rod 53, being attached to the 35 actuator cables 51 and 52, carries said cables upward with it, thereby rocking the rockers 30 and 47 forward on their pivots 31 and 48, respectively, and causing the cable 50 to move down. The rocker 30, in the forward 40 movement just imparted to it, takes with it the connected portion of the cable 26 and so draws on said cable and causes the same to draw up the branch 29 and shift the reaches 22 and 20, until the parts are neutrally disposed, as in Fig. 4. The shifting of the reaches 20 and 22 shuts off the power from 45 the elevator. It has been explained how the same result is attained with the rocker 157.

Meanwhile the weight 103 yields to relieve 50 the cord 55 to whatever extent may be necessary, by permitting a sufficient amount of said cord to be drawn to the right, from beneath the sheave 67, to make up or provide for any excessive deflection of said cord.

55 After the elevator comes to a stop, the lever 95 is thrown forward to reset the trip mechanism, unless said elevator had continued far enough, after the power was disconnected, so that the cam 93 has caused 60 said mechanism to be reset, and it remained reset. In either event, the tooth 90 is thrown out of engagement with the rack 80, and the actuator is left free. The actuator being free, the cable reaches 20 and 22 can be manipulated to start the elevator in either di-

rection. When either of the said reaches next moves or is moved downward, it carries with it the attached branch (28 or 29), and, through the medium of such branch, draws on the cable 26, and causes the latter to rock 70 back the actuator and leave the same in readiness for subsequent active operation. The springs 154 and 160 perform a similar service for the actuator in the other example.

Assuming that the cable reaches 20 and 22 and the cable branches 28 and 29 are disposed as in Fig. 3, when the elevator is descending, and that the platform 6 is approaching the floor 4, and assuming, furthermore, that the cord 56 is deflected, either 80 by force applied to some one or more of the cords 59 or directly to said cord 56 itself, (or the force may be applied to said cord 56 through the medium of the netting 61, especially when the elevator is approaching 85 more nearly to the bottom of the well), said cord 56 exerts a pull on the latch 119 and causes said latch to release the plunger 118 to the spring 125, when said spring forces said plunger upwardly, and thereby causes 90 the arm 121 and the wedge-block 120 to be rocked in the same direction. In its upward movement the wedge-block 120 grips the cable 50. The cable 50 is carried down with the descending elevator, and the actuator 95 rocked to shut off the power, by means of either the neutralizer or the electric switch, the action of each being the same as when said actuator is operated through the medium of the landing trip mechanism. In the case 100 of the shift cable, the positions of the parts change from those shown in Fig. 3 again to those shown in Fig. 4.

Meanwhile the spring 135 yields to relieve 105 the cord 56 to whatever extent may be necessary, by permitting a sufficient amount of said cord to be drawn to the right, from beneath the sheave 70, to take up or provide for any excessive deflection of said cord.

After the elevator comes to a stop, the 110 lever 145 is thrown forward to reset the trip mechanism. In the resetting operation the cable 50 is released from the grip of the wedge-block 120. The actuator is now free, and it is restored to initial position by either 115 of the agencies and in either manner already very fully described and set forth.

The spring 141 enables the elevator to 120 continue its descent, after the power has been shut off by the action or through the medium of the actuator, without tripping the cable 50 or doing other injury or damage, as has been explained.

When the actuator is operated through 125 the medium of the clutch carried by the elevator and which includes the wedge-block 120, at the time the actuator cable 50 is grasped by such clutch, the slide 87 on the actuator rod 53 moves upwardly toward the upper arm 107, and may be stopped by said 130

arm, in which event, or in case the active movement of said elevator be stopped by some other means, as by the neutralizer when movement thereof is exhausted by said actuator, said clutch slips on said cable, unless or until said elevator comes to a stop. When the actuator is returned to normal position, the slide 87 is carried down to the starting point, which is on or in close proximity to the lower arm 107.

The actuator may be counterweighted to counterbalance the rod 53 and attached parts, which are provided for each floor, and as a rule should be counterweighted in order to lessen the force required to rock said actuator to stop the elevator. In Figs. 1 and 5 I show one means of applying a counterbalance to the actuator, such means consisting of a weight 166 suspended by a cord 165 from a pin 54 which projects from the rocker 47 adjacent to the lower, front corner thereof. This weight counterbalances the rod 53 and attached parts and so relieves the actuator from the weight of said rod and parts as a restraining factor when said actuator is operated by either trip mechanism.

What I claim as my invention, and desire to secure by Letters Patent, is—

1. In a safety appliance for elevators, a yielding guard comprising a horizontal flexible member adapted when deflected to exert an end pull, supporting means back of said member, and a plurality of movable members between said first-named member and said means.

2. In a safety appliance for elevators, a yielding guard comprising a horizontal flexible member adapted when deflected to exert an end pull, supporting means back of said member, and a netting between said member and said means.

3. In a safety appliance for elevators, a yielding guard comprising a horizontal flexible member adapted when deflected to exert an end pull, supporting means above said member, supporting means back of said member, a plurality of movable members between said first-named member and said first-named supporting means, and a plurality of movable members between said first-named member and said second-named supporting means.

4. A safety appliance for elevators comprising, with the means for shutting off the power, an oscillatory actuator for such means, such actuator consisting in part of a cable, a yielding guard consisting in part of a flexible member adapted when deflected to exert an end pull, trip mechanism between said guard and said actuator cable adapted to be tripped by the former and then to cause said actuator to be operated, such trip mechanism consisting in part of a normally-engaged latch to which one end of said flexible member is attached, and which is

disengaged when said member is deflected, and hand operated setting means for said mechanism.

5. A safety appliance for elevators comprising, with means for shutting off the power, an actuator for such means, a yielding guard, and trip mechanism between said guard and said actuator, adapted to be tripped by the former and then to cause the latter to be operated, such trip mechanism being provided with automatic safety means to prevent damage to said actuator after said power has been shut off.

6. A safety appliance for elevators comprising, with means for shutting off the power, an actuator for such means, a yielding landing guard, and landing trip mechanism between said guard and said actuator, adapted to be tripped by the former and then to cause the latter to be operated, such trip mechanism being provided with automatic means to disengage said trip mechanism and release said actuator, after said power has been shut off.

7. A safety appliance for elevators comprising, with means for shutting off the power, an oscillatory actuator for such means, said actuator consisting in part of a cable, a yielding elevator guard, and elevator trip mechanism between said guard and said actuator cable, adapted to be tripped by the former and then to cause said actuator to be operated, such trip mechanism consisting in part of gripping means for said cable, which gripping means is adapted to slip on said member after said power has been shut off.

8. In a safety appliance for elevators, the means accessible from the elevator for shutting off the power, an oscillatory actuator adapted to operate said means and to be thereby returned to initial position, said actuator consisting in part of a cable, trip mechanism to actuate said cable in one direction, said mechanism consisting in part of a normally-engaged latch, and a yielding guard attached to said latch and adapted when it yields to disengage the same and so to trip said mechanism.

9. The combination, in a safety appliance for elevators, with the reaches of a power-controlling cable, of an oscillatory actuator consisting in part of a cable, a neutralizer having a branch connected with each of said reaches, said neutralizer being operatively connected with said actuator, and automatic means to operate said actuator through said cable in the direction to actuate said neutralizer and cause the same to shift said first-named cable.

10. The combination, in a safety appliance for elevators, with the reaches of a power-controlling cable, of an oscillatory actuator consisting in part of a cable, a neutralizer having a branch connected with

- each of said reaches, said neutralizer being operatively connected with said actuator, a tension device for said neutralizer, and automatic means to operate said actuator 5 through said cable in the direction to shift said first-named cable.
11. The combination, in a safety appliance for elevators, with the reaches of a power-controlling cable, of an oscillatory actuator, 10 a flexible member having one end fast and branches at the other end connected with said reaches, supporting sheaves for said member, one of such sheaves being carried by said actuator, and automatic means to 15 operate said actuator in the direction to shift said cable.
12. The combination, in a safety appliance for elevators, with the reaches of a power-controlling cable, of an oscillatory 20 actuator, a flexible member having one end fast and branches at the other end connected with said reaches, supporting sheaves for said member, one of such sheaves being carried by said actuator, a yielding arm carrying 25 another of such sheaves, and automatic means to operate said actuator in the direction to shift said cable.
13. The combination, in a safety appliance for elevators, with an elevator provided 30 with a serrated member, the power-controlling means, an oscillatory actuator for such means, and a yielding landing guard, of a spring-pressed rock-shaft and latch, the latter having said guard connected therewith,
- 35 a lug for said latch, a sliding member attached to said actuator, a toothed member pivotally connected with said sliding member, and connections between said rock-shaft and said toothed member, the construction and arrangement being such that, when said latch is tripped, said rock-shaft operates said connections and causes said toothed member to engage said serrated member.
- 40 14. The combination, in a safety appliance for elevators, with an elevator provided with a serrated member, the power-controlling means, an oscillatory actuator for such means, and a yielding guard, of a spring-pressed rock-shaft and latch, the latter having said guard connected therewith, a lug for said latch, a sliding member attached to said actuator, a toothed member pivotally connected with said sliding member, connections between said rock-shaft and said toothed member, the construction and arrangement being such that, when said latch is tripped, said rock-shaft operates said connections and causes said toothed member to engage said serrated member,
- 45 50 55 60 65 70 75 80 85 90 95 100 105 110 115 120 125 130
- means, and a yielding guard, of a spring-pressed rock-shaft and latch, the latter having said guard connected therewith, a lug for said latch, a sliding member attached to said actuator, a toothed member pivotally connected with said sliding member, connections between said rock-shaft and said toothed member, the construction and arrangement being such that, when said latch is tripped, said rock-shaft operates said connections and causes said toothed member to engage said serrated member, and a cam in the path of said toothed member, adapted to disengage the latter from said serrated member.
16. The combination in a safety appliance for elevators, with an elevator provided with a serrated member, the power-controlling means, an oscillatory actuator for such means, and a yielding guard, of a spring-pressed rock-shaft and latch, the latter having said guard connected therewith, a lug for said latch, a sliding member attached to said actuator, a toothed member pivotally connected with said sliding member, connections between said rock-shaft and said toothed member, the construction and arrangement being such that, when said latch is tripped, said rock-shaft operates said connections and causes said toothed member to engage said serrated member, and hand-operated means to set the parts and engage said latch with said lug.
17. The combination, in a safety appliance for elevators, with an elevator provided with a serrated member, the power-controlling means, an oscillatory actuator for such means, and a yielding guard, of a spring-pressed rock-shaft and latch, the latter having said guard connected therewith, a lug for said latch, a sliding member attached to said actuator, a toothed member pivotally connected with said sliding member, connections between said rock-shaft and said toothed member, the construction and arrangement being such that, when said latch is tripped, said rock-shaft operates said connections and causes said toothed member to engage said serrated member, a block loosely mounted on said rock-shaft, a lever pivotally attached to said block, said lever having a lug, and a lug extending from said rock-shaft into operative relation to said first-named lug.
18. The combination, in a safety appliance for elevators, with an elevator provided with a serrated member, the power-controlling means, an oscillatory actuator for such means, such actuator including a rod, a guide for said rod, and a yielding guard, of a spring-pressed rock-shaft and latch, the latter having said guard connected therewith, a lug for said latch, a sliding member attached to said rod, a toothed member pivotally connected with said sliding member,

and connections between said rock-shaft and said toothed member, the construction and arrangement being such that, when said latch is tripped, said rock-shaft operates said connections and causes said toothed member to engage said serrated member.

19. The combination, in a safety appliance for elevators, with an elevator carrying a serrated member, the power-controlling means, an oscillatory actuator for such means, and a yielding guard, of a spring-pressed rock-shaft and latch, the latter having said guard connected therewith, a lug for said latch, a sliding member attached to 10 said actuator, a toothed member pivotally connected with said sliding member, and swivel connections between said rock-shaft and said toothed member, the construction and arrangement being such that, when said latch is tripped, said rock-shaft operates 15 through said connections to cause said toothed member to engage said serrated member.

20. The combination, in a safety appliance for elevators, with the power-controlling means, an actuator for such means, and a yielding guard, of trip mechanism between said guard and said actuator, such mechanism consisting in part of a rock-shaft provided with an arm, a latch pivotally connected with said arm, and with which said guard is connected, a lug for said latch, and a spring attached to said arm and latch.

21. In a safety appliance for elevators, the elevator, the hand-operated means which is accessible from said elevator for shutting off the power, an oscillatory actuator for such means, said actuator consisting in part of a cable, and mechanism adapted to connect said cable with said elevator, when the latter is ascending.

22. In a safety appliance for elevators, the elevator, the hand-operated means which is accessible from said elevator for shutting off the power, an oscillatory actuator for such means, said actuator consisting in part of cables, mechanism adapted to connect one of said cables with said elevator, when the latter is ascending, and mechanism adapted 45 to connect the other of said cables with said elevator, when the latter is descending.

23. In a safety appliance for elevators, the power-controlling means, an actuator for such means, such actuator consisting in part of a cable, an elevator provided with a clutch for said cable, automatic means to cause said clutch to grip said cable, and means to permit said clutch to slip on said cable after said actuator has been operated.

60 24. The combination, in a safety appliance for elevators, of an elevator provided with an abutment, and with a pivotally-mounted wedge-block, the hand-operated means which is accessible from said elevator

for shutting off the power, an oscillatory actuator for such means, such actuator consisting in part of a cable which passes between said abutment and wedge-block, and means carried by said elevator to actuate said wedge-block into gripping position.

25. The combination, in a safety appliance for elevators, of an elevator provided with an abutment, and with a pivotally-mounted wedge-block, the hand-operated means which is accessible from said elevator 75 for shutting off the power, an oscillatory actuator for such means, such actuator consisting in part of a cable which passes between said abutment and wedge-block, means carried by said elevator to actuate 80 said wedge-block into gripping position, and adjustable means to limit the movement of said wedge-block when actuated into gripping position.

26. The combination, in a safety appliance for elevators, of an elevator having an engaging member, and provided with an abutment, and with a pivotally-mounted spring-pressed, wedge-block, the hand-operated means which is accessible from said elevator for shutting off the power, an oscillatory actuator for such means, such actuator consisting in part of a cable, means carried by said elevator to actuate said wedge-block into gripping position, and trip mechanism consisting in part of an oscillatory member which is attached to said cable and adapted to be thrust into the path of said engaging member, when said mechanism is tripped, the construction and arrangement of parts being such that said hand-operated means is actuated by said elevator through said actuator to stop the elevator when descending, and said hand-operated means is actuated by said elevator 95 through said actuator to stop the elevator 100 when ascending.

27. The combination, in a safety appliance for elevators, with the power-controlling means, and an actuator therefor, such actuator consisting in part of a cable, of an elevator having a supporting member, said member being provided with an abutment and with a lug, a slotted wedge-block having a lug to engage said first-named lug, a pivot passing through the slot in said wedge-block, at one end, into said supporting member, a spring in said slot between the other end of said slot and said pivot, said cable passing between said abutment and wedge-block, and means carried by said elevator to actuate said wedge-block into gripping position.

28. The combination, in a safety appliance for elevators, with the power-controlling means, and an actuator therefor, such actuator consisting in part of a cable, of an elevator having a supporting member, said

member being provided with an abutment and with a lug, a slotted wedge-block having a lug to engage said first-named lug, a pivot passing through the slot in said 5 wedge-block, at one end, into said supporting member, a spring in said slot between the other end of said slot and said pivot, said cable passing between said abutment and wedge-block, means carried by said 10 elevator to actuate said wedge-block into gripping position, and a setting lever rising from said wedge-block.

29. The combination, in a safety appliance for elevators, with the power-controlling means, and an actuator therefor, such actuator consisting in part of a cable, of an elevator provided with an abutment, and with a pivotally-mounted wedge-block, said cable passing between said abutment 15 and said wedge-block, an arm extending from said wedge-block, a spring-pressed plunger in engagement with said arm, a spring-pressed latch adapted to retain said plunger with its spring under compression, and a yielding guard connected with said 20 latch, said plunger, latch, and guard being carried by said elevator.

30. In a safety appliance for elevators, the power-controlling means, an actuator 25 for such means, an elevator having an engaging member, and equipped with trip mechanism adapted when tripped and the elevator is descending to engage said actuator and stop said elevator, and trip mechanism connected with said actuator, and provided with an engaging member 30 which is adapted, when said mechanism is tripped and the elevator is ascending, to

be thrust into the path of said first-named engaging member and stop said elevator. 40

31. In a safety appliance for elevators, an elevator, hand-operated means which is accessible from said elevator for shutting off the power, an oscillatory actuator for such means, said actuator consisting in part 45 of cables, means to operate through one of said cables said actuator from said elevator when ascending, whereby said hand-operated means is actuated by said elevator through said actuator to stop the elevator, 50 and means to operate through the other of said cables said actuator from said elevator when descending, whereby said hand-operated means is actuated by said elevator through said actuator to stop the elevator. 55

32. In a safety appliance for elevators, an elevator, the power-controlling means, an actuator for such means, interlocking means to operate said actuator from said elevator when ascending, and clutch means to operate said actuator from said elevator when descending. 60

33. In a safety appliance for an elevator, the power-controlling means other than the valve or equivalent mechanism, an actuator 65 therefor, such actuator comprising cable-connected upper and lower rocking members, trip mechanism attached to one of the actuator cables, and counterbalancing means attached to said actuator for said 70 trip mechanism.

EDWARD TURGEON.

Copies of this patent may be obtained for five cents each, by addressing the "Commissioner of Patents.
Washington, D. C."

It is hereby certified that the name of the patentee in Letters Patent No. 1,314,228, granted August 26, 1919, for an improvement in "Safety Appliances for Elevators," was erroneously written and printed as "Edward Turgeon," whereas said name should have been written and printed as *Edmond Turgeon*; and that the said Letters Patent should be read with this correction therein that the same may conform to the record of the case in the Patent Office.

Signed and sealed this 14th day of October, A. D., 1919.

M. H. COULSTON,

[SEAL.]

Acting Commissioner of Patents.
